CLAIM

The ornamental design for an inflatable aircraft bed with a vacuum bag, as shown and described.

DESCRIPTION

FIG. 1 is an exploded top perspective view of an inflatable aircraft bed and vacuum bag, showing my new design;

FIG. 2 is an exploded front view thereof;

FIG. 3 is an exploded rear view thereof;

FIG. 4 is an exploded side view thereof;

FIG. 5 is an exploded opposite side view thereof;

FIG. 6 is a top plan view thereof; and,

FIG. 7 is a bottom plan view thereof.

The broken lines are for the purpose of illustrating portions of the article that form no part of the claim.

1 Claim, 7 Drawing Sheets
